Patented Mar. 12, 1918.

UNITED STATES PATENT OFFICE.

THOMAS J. THOMPSON, OF CLIMAX, MINNESOTA.

STORM-WINDOW FASTENER.

1,258,826.

Specification of Letters Patent. Patented Mar. 12, 1918.

Application filed March 22, 1917. Serial No. 156,630.

To all whom it may concern:

Be it known that I, THOMAS J. THOMPSON, a citizen of the United States, residing at Climax, in the county of Polk and State of Minnesota, have invented certain new and useful Improvements in Storm-Window Fasteners; and I do hereby declare the following to be a full, clear, and exact description of the invention, such as will enable others skilled in the art to which it appertains to make and use the same.

My invention relates to storm window sash fasteners; and, to this end, it consists of the novel devices and combinations of devices hereinafter described and defined in the claim.

In the accompanying drawings, which illustrate the invention, like characters indicate like parts throughout the several views.

20 Referring to the drawings,

Figure 1 is a vertical section taken centrally through a window frame, upper and lower window sashes and a storm window sash, said storm window sash being secured 25 to a window frame by a pair of the improved fasteners;

Fig. 2 is a perspective view of the storm window sash removed from the window frame; and

30 Fig. 3 is a fragmentary view, showing in side elevation one of the improved fasteners and also showing in section one of the co-operating lock studs.

The numeral 4 indicates a window frame 35 having the customary inner, intermediate and outer sash stops 5, 6 and 7, respectively. Upper and lower window sashes are hung between the stops 5, 6 and 7 for vertical sliding movement and are indicated, respectively, by the numerals 8 and 9. A storm window sash 10 is fitted in the window frame 4 and seated against the outer stop 7.

The numeral 11 indicates a pair of angle bars, which constitute the movable members 45 of the improved fasteners. One of the flanges 12 of these angle bars 11 rests flat against the inner faces of the stiles of the storm window sash 10, and are connected thereto for limited endwise sliding movement by a plurality of longitudinally spaced slot and pin connections 13. The slots of these connections 13 are formed in the flanges 12, while the pins thereof are secured to and project laterally from the storm window sash 10. These pins are provided 55 with heads, which prevent the angle bars 11

from becoming detached therefrom and, as shown, are preferably in the form of round-headed screws.

The other flanges of the angle bars 11 extend at right angles from the storm window sash 10 to afford lock blades 14, having formed therein oblique cam slots 15, open at their outer ends and arranged to engage and interlock with headed studs 16. These headed studs 16 are secured to and project from the outer stops 7 and, as shown, are preferably in the form of round-headed screws. The angle bars 11 extend substantially the full length of the stiles of the storm window sash 10, with just sufficient clearance between the top of the window frame 4 and the sill thereof to permit the required endwise movement of said angle bars. On the lower end portions of the angle bars 11, are 75 hand holds 17.

By the use of the improved fasteners, it is possible to put on or take off a storm window sash from the inside of a building. To put on the storm sash 10, the lower sash 80 9 is first raised and the said storm sash inserted endwise through the window frame to the outside of the building and then raised and supported on the window-sill. While the storm window sash 10 is in this 85 position, the same may be held by the hand holds 17 and, at the same time, the angle bars 11 moved to their uppermost positions to carry the flaring open ends of the cam slots 15 into registration with the lock pins 90 16. Then by drawing inward and downward on the hand holds 17, the cam slots 15, acting on the pins 16, will draw the storm window sash 10 firmly against the stop 7 throughout its entire length. As there is a 95 multiplicity of these cam slots 15 and co-operating pins 16, the storm window sash 10 cannot spring away from the window stop 7, and if the same is warped, at the time the same is put on, the lock blades 14 100 will draw the same back into its original position.

The fastener is not, of course, limited for use in connection with storm window sashes, but may be generally used for securing in 105 position window screens, panels, and the like.

What I claim is:

A sash fastener comprising a plurality of lock studs projecting from the upright sash 110 stops of a window frame, and a pair of angle bars having one of their flanges se-

cured by slot and headed pin connections to the inner faces of the stiles of the window sash with freedom for limited endwise movement, the other flanges of the angle bars being turned outward and away from the window sash to closely fit between said window stops and having cam slots arranged to be moved into and out of interlocking en-

gagement with said lock studs by an endwise movement of the angle bar.

In testimony whereof I affix my signature in presence of two witnesses.

THOMAS J. THOMPSON.

Witnesses:

NORMAN ROSHOLT,
C. M. KNUTSON.
